SCISSORS SHARPENER

Filed Dec. 21, 1948

UNITED STATES PATENT OFFICE

2,556,202

SCISSORS SHARPENER

William M. Littleton, Dublin, Ga.

Application December 21, 1948, Serial No. 66,475

1 Claim. (Cl. 51—58)

1

This invention relates to an improved scissor sharpener, and more particularly to a light-weight, portable scissor sharpener which may be used by persons unskilled in the art of sharpening cutlery to provide a suitable and desirable cutting edge on the scissor blades.

Another object of this invention is to provide a scissor sharpener of the kind to be more particularly described hereinafter, which is so constructed and arranged that it may be manufactured at a low, reasonable cost, to permit a wide distribution.

A further object of this invention is to provide a scissor-sharpening tool of this kind having spring-pressed, clamping members for securing the blades of the scissors and the sharpening element to the device, the clamping members being so formed that they may be readily opened by finger pressure of the operator.

Yet another object of this invention is to provide a scissor-sharpening tool of this kind having provision for changing the sharpening element. The sharpening element is supported on the tool for movement along the edge of a cutting blade to be sharpened, and so supported on the tool that the cutting element may be adjusted to various, selected, longitudinal and angular positions to accommodate the particular length and the angle of the blade to be sharpened.

With the above and other objects in view, my invention consists in the arrangement, combination and details of construction disclosed in the drawings and specification, and then more particularly pointed out in the appended claim.

In the drawings:

Figure 1 is a side elevation of a scissor sharpener constructed according to an embodiment of my invention;

Figure 2 is a front elevation thereof;

Figure 3 is a top plan view;

Figure 4 is a fragmentary detail section, taken on the line 4—4 of Figure 1.

Referring to the drawings, the numeral 10 designates generally a scissor-sharpening tool constructed to an embodiment of my invention, which is portable in nature, to be moved where desired, or readily carried about by a person desiring to use the tool at any particular position or locality.

The sharpening tool 10 is formed of a flat base member 11, which constitutes a supporting plate for the scissors to be sharpened and the sharpening element to be engaged with the blades of the scissors.

A spring-pressed, clamping member 12 is carried by the forward edge to support a blade of the scissors along one edge of the supporting plate or base 11. The clamping member 12 consists of a pair of face-abutting jaw members 14 and 15, each having a handle portion, as 16 and 17, respectively, for engagement through a split ring or sleeve 18. The longitudinal free edges of the split ring 18 engage the outer faces of the jaw members 14 and 15 for pressing the jaw members together. The handle portions 16 and 17 extend through openings, as 19, intermediate the length of the resilient sleeve 18 substantially opposite from the split ends of the tube. The formation of the clamping member 12 is such that the handles 16 and 17 are substantially pivoted in the openings 19 for pressing the jaw members 14 and 15 divergently apart upon moving of the handles 16 and 17 together.

20 The forward, marginal edge, as 20, of the base plate 11 is downturned at right angles to the plane of the plate to provide for the attachment of the clamping member 12. The lower edge of the downturned flange 20 is provided at the 25 corners thereof with a rearwardly-bent ear portion 21 which is adapted to clampingly engage one of the jaw members, as 14, for securing that jaw member to the back side of the flange 20. The jaw 15 is disposed on the opposite side of the flange 20 and the upper edges of the jaw members 14 and 15 are disposed slightly below the plane of the upper surface of the base member 11. The clamping member 12 is adapted to secure a blade, as B, of a pair of scissors on the forward edge of the base 11, in such a manner that the cutting edge of the blade B will be disposed above the plane of the upper surface of the base plate 11 for engagement with a sharpening element E, to be described hereinafter.

30 A sharpening element E is adapted to be supported above the upper surface of the base 11 for engagement with the edge of the blade B of the scissors S to be sharpened. The sharpening element E is adapted to be clamped in a resilient clamping member, as 22, above the base 11. An arm, as 24, is pivotally mounted on the upper surface of the base 11 by a pin 25 which extends through the base 11 and through one end of the arm 24. The end of the arm 24 is spaced upwardly from the base member 11 by a suitable washer or spacer 26 about the pin 25. The forward end of the arm 24 is bent upwardly substantially at right angles to the length of the arm 24, as clearly shown in Figure 1 of the drawings.

35 The clamping member 22 is adapted to be pivot-

ally mounted on the upper end of the upwardly-extending portion 27 at the forward end of the arm 24.

The clamping member 22 is formed in substantially the same manner as the clamping member 12 described above. The clamping member 22 is formed with a pair of spring-pressed, clamping jaws 28 and 29 carried by a split ring or tubular member 30.

The arms 31 and 32 formed integrally with the jaw members 28 and 29, respectively, are adapted to engage through slots intermediate the length of the sleeve 30 opposite from the split edges. The handles 31 and 32 are substantially pivoted in the slots in the tube 30, whereby upon rocking movement of the handles 31 and 32 divergently together, the jaw members 28 and 29 are moved divergently apart for receiving therebetween the sharpening element E. A pivot pin, as 34, is loosely engaged between the jaw members 28 and 29 at one end thereof. The pin is so engaged between the jaws 28 and 29 that the jaws may be moved apart when it is desired to clamp the sharpening element E therebetween, the engagement of the pin 34 in the jaws 28 and 29 being such that the free movement of the jaw members may be effected by pressing on the handles 31 and 32. The pin 34 is secured on the upper end of the free end portion 27 of the arm 24.

In the use and operation of the scissor-sharpening tool 18, described above, a blade B of the scissors to be sharpened is clamped between the jaws 14 and 15 of the clamping member 12. The cutting edge of the blade B is disposed above the surface of the supporting plate 11. A suitable rubber bead or cushion, as 36, is carried by the clamping member 12 between one of the jaw members, as 15, and the surface of the blade B. The cushioning member 36 provides for the application of a clamping force along the length of the blade B between the jaws of the clamping member, and provides for a uniform force to be applied along the entire area of the blade B clamped in the member 12.

A sharpening element E, which may be of carborundum, or other suitable abrasive material, is adapted to be resiliently clamped between the jaws 28 and 29 of the clamping member 22. The sharpening element E is secured between the jaw members 28 and 29 by the force of the resilient sleeve or tube 30. As the sharpening element E is only resiliently secured between the clamping members 28 and 29, it may be adjusted to any desired position along the length of the jaw members, and the angular relation between the jaw members and the sharpening element may be suitably adjusted as desired. In this manner, the sharpening element E may be supported for engaging the cutting edge of the blade B at any desired angle. For removing or adjusting the sharpening element E, the clamp 22 may be pivoted upwardly about the pivot pin 34 so that the sharpening element E may be positioned between the jaws 28 and 29 free from any obstruction of the base 11.

When the scissor blade B is positioned in the clamp 12, and the sharpening element E is secured in the clamp 22 as desired, the clamp 22 is pivoted downwardly about the pin 34 so that the sharpening element E will engage the cutting edge of the blade B. The operator may then grasp the handles 31 and 32 and rock the clamping member 22 about the pivot 25, which secures the arm 24 to the base 11. Rocking of the clamping member 22 and the sharpening element E about the pivot 25 will provide for the movement of the sharpening element E along the length of the cutting edge of the blade B to provide for the desired sharpening of the blade.

I do not mean to confine myself to the exact details of construction herein disclosed, but claim all variations falling within the purview of the appended claim.

Having thus described my invention, I claim:

20 A scissors sharpening device comprising a flat base member, a spring pressed clamping member fixed on one edge of said base member for securing a scissors blade to be sharpened, said clamping member being provided with a rubber cushion member which serves to insure the application of a uniform force over the entire area of a scissors blade held in said clamping member, an arm pivoted at one end thereof on said base member for pivotal movement only in a plane parallel to the 30 plane of said base member, a second spring pressed clamping member including a pair of separable jaws, a pivot pin on said arm loosely extending through said jaws for securing said second clamping member on said arm for pivotal movement thereon in a plane at right angles to the plane of said base, and a sharpening element supported in said second clamping member for engagement with said blade to be sharpened.

40 WILLIAM M. LITTLETON.
